UNITED STATES PATENT OFFICE.

NORMAN B. HURD, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

LOCK-STRIKE.

1,005,841.

Specification of Letters Patent.

Patented Oct. 17, 1911.

Application filed June 13, 1911. Serial No. 632,895.

To all whom it may concern:

Be it known that I, NORMAN B. HURD, a citizen of the United States, residing at New Britain, Hartford county, State of Connecticut, have invented certain new and useful Improvements in Lock-Strikes, of which the following is a full, clear, and exact description.

My invention relates to improvements in locks and relates particularly to an improved strike-plate so-called, whereby the latch action will be rendered noiseless.

In the accompanying drawings, Figure 1 is a front elevation of a strike-plate of conventional form provided with my improvement. Fig. 2 is a vertical central sectional view. Fig. 3 is a rear elevation. Figs. 4 and 5 are views of details.

It should be understood that in the accompanying drawings, I have shown my invention in a preferred form, and that I clearly apprehend that various modifications and changes may be made without departure from the spirit and scope thereof.

The improved features of construction are embodied in this instance, wholly in the strike-plate, and since said strike-plate can be used with any well-known spring latch, it is obvious that no illustration or detailed description of said latch mechanism is necessary. As is well known, when a door provided with a spring latch is closed, the latch after being repressed by the strike-plate, snaps forwardly with a distinctly audible click as soon as it faces up with the usual opening or hole therein.

In many places, such as hotels, institutions for the sick, and the like, this clicking noise is a common source of irritation to the occupants of the rooms. To that end my invention aims at preventing this clicking noise, and to attain that end, I have provided in the strike-plate itself means to so retard the projection of the latch bolt that it will move with relative slowness into the locking position.

1 represents a strike-plate of the ordinary outline. This strike-plate is provided with the usual forward projection 2 which is encountered by the latch-bolt as the door is being closed, and by which said bolt is repressed. The strike-plate is likewise provided with an opening at the proper position into which the latch is projected when the door is fully closed. This opening is

guarded by a repressible filler-plate 1^a, which, when the door is open, may lie flush, or substantially so, with the outer surface of the strike-plate. When, however, the door is closed, this filler-plate 1^a may be forced inwardly to afford room for the projected latch bolt. In the particular form of the device shown in the drawings, the strike-plate has the rearward extensions 3, which extensions carry a plate 4, which plate 4 has a rearwardly extending cylinder 5. The rear of the filler-plate 1^a is provided with a piston 6 adapted to fit with reasonable snugness within the cylinder 5.

7 is a spring, preferably provided for forcing the filler-plate 1^a forwardly to close the latch opening in the strike-plate.

8 is a vent passage in the piston 6. 9 is a check valve adapted to said passage. This check-valve may be of any suitable type, for example, a ball check, as shown.

10 is a packing which may be provided, if desired, said packing being held in place by a screw 11. The cylinder 5 acts, in effect, like a dash-pot, retarding the inward movement of the piston 6. The valve 9 operates in a direction to vent the dash-pot as the piston is being moved outwardly under the influence of spring 7. In this connection it ought to be stated, that when the screw 11 is provided, the vent passage 8 may extend directly through the screw.

From the foregoing it will be seen that the filler-plate 1^a may readily be repressed, and yet will be sufficiently cushioned so that said repressing movement will be comparatively slow. It follows that when said filler-plate 1^a is repressed by the action of the latch bolt, it will stand in front of the latch bolt and gradually recede, thereby preventing any sharp click, or snapping noise, such as is occasioned when a latch bolt is projected in the ordinary manner into the opening in an ordinary strike-plate. Of course when the latch is retracted the filler-plate 1^a moves freely out. Any suitable means may be provided for guiding the filler-plate 1^a, for example, the rearward extensions 3-3, so that when said filler-plate is advanced it will enter the opening in the strike-plate properly.

While I am aware that means have been provided in latch mechanisms to retard the forward movement of the latch-bolt to prevent said objectionable click of the latch,

this has not been prevented by any improvement in the construction of the strike-plate itself. By providing said means in said strike-plate, it is possible at nominal expense to equip a building already provided with locks and latches, with means to overcome the objection referred to and without disturbing or changing over in the slightest the latch mechanism.

10 What I claim is:

1. In a strike-plate for spring-latches, a face-plate, an opening therein, means arranged to normally stand within said opening to receive and check the forward movement of the latch therein, and means to retard the repression of the latch resisting means, and a spring for projecting said latch resisting means.

2. In a strike-plate for spring-latches, a face-plate having a latch opening therein, means standing in said opening arranged

to check the projection of a latch into said opening, said means including a dash-pot.

3. In a strike-plate for spring-latches, a face-plate having a latch opening therein, 25 means standing in said opening arranged to check the projection of a latch into said opening, said means including a dash-pot, and a spring for projecting said latch retarding means.

4. In a strike-plate for spring-latches, a face plate, an opening therein, a closer plate arranged to normally close said opening, a spring to yieldingly resist the repression of the plate and a fluid check co-acting with 35 the spring to resist said repression of the plate, said check offering substantial end resistance to the projection of said plate.

NORMAN B. HURD.
